United States Patent Office

Des. 196,936
Patented Nov. 19, 1963

196,936

TUBE CUTTER

George E. Franck, Morton Grove, Ill., assignor to Imperial-Eastman Corporation, a corporation of Illinois

Filed Nov. 26, 1962, Ser. No. 72,605

Term of patent 14 years

(Cl. D54—13)

FIG. 1

FIG. 2

FIG. 3

FIG. 4

FIG. 5

FIGURE 1 is a righthand side elevation of a tube cutter embodying my new design;

FIGURE 2 is a lefthand side elevation thereof;

FIGURE 3 is a front elevation thereof;

FIGURE 4 is a rear elevation thereof; and

FIGURE 5 is a top plan view thereof.

I claim :

The ornamental design for a tube cutter, as shown.

References Cited in the file of this patent

UNITED STATES PATENTS

1,945,949	Myers	Feb. 6, 1934
2,231,593	Pritchard	Feb. 11, 1941
2,284,133	Condon	May 26, 1942